[57] ABSTRACT

An exposure determining device comprises a bridge circuit which includes at least a photoelectric element for receiving light from an object to be photographed and a variable resistor for controlling the balance of the bridge circuit and associated with exposure factors. The device further comprises a bridge balance detecting circuit producing one of first and second signals upon unbalance of the bridge circuit, and an electric motor rotatable in forward and reverse directions by first and second driving circuits operable in response to the first and second signals, respectively. The motor is associated with the resistor in such a manner that the resistance value of the resistor is decreased during the rotation of the motor in one direction and is increased during the rotation of the motor in the other direction. The opposite terminals of the motor may be short-circuited by a short-circuiting circuit. A relay circuit is provided for closing the first and second driving circuits in response to the first and second signals, respectively, and for closing the short-circuiting circuit upon balance of the bridge circuit.

FIG. I

FIG. 2

EXPOSURE DETERMINING DEVICE

BACKGROUND OF THE INVENTION

1. Field of the Invention

This invention relates to the stabilization of an automatic photographic exposure determining device having a feedback circuit commonly known as a servo circuit.

2. Description of The Prior Art

In a known automatic exposure determining device of the described type, the stabilization of the servo system has been accomplished by providing an internal feedback referred to as "speed feedback" thereby to reduce the constant speed of a servo motor. This may qualitatively be explained as follows: among the elements constituting the servo system, movable members such as a drive motor, reduction gearing, the member to be controlled, etc., have their own masses which, when moving, generate a moment of inertia resulting in various phenomena such as hunting, overshoot, etc., which, in turn, aggravate the damping of the servo system. Therefore, speed feedback has been employed to reduce the constant speed of the motor and thereby reduce the effect of the moment of inertia, thus improving the damping. Generally, in the method employing speed feedback, a tachometer generator has been provided on the output shaft of the drive motor to detect the rotational speed of the output shaft and apply a feedback to the drive motor. This method, however, suffers from disadvantages in that the output of the drive motor is consumed into the rotation of the tachometer generator, that the use of such generator makes it difficult to provide a compact construction, and that the constant speed reduced by the application of speed feedback leads to a reduced response speed.

SUMMARY OF THE INVENTION

In view of the fact that short-circuiting of the armature winding on a compact DC motor causes an electromagnetic brake to be applied to the motor, and this acts effectively as a damper, the present invention intends to eliminate the above-noted disadvantages and stabilize the servo system by arranging the motor so that it acts as a drive motor during its energized condition and acts as a damper during its deenergized condition.

To achieve this object, the present invention provides an exposure determining device which comprises a bridge circuit including at least a photoelectric element adapted to receive the light from an object to be photographed and a variable resistance element for controlling the balance of said bridge circuit and associated with exposure factors. A circuit for detecting the balance of the bridge circuit is provided and produces one of first and second signals upon unbalance of the bridge circuit. An electric motor, rotatable in forward and reverse directions, is operatively associated with the resistance element in such a manner that the resistance value of the resistance element is decreased when the electric motor rotates in one direction and is increased when the electric motor rotates in the other direction. The device further comprises a circuit for short-circuiting both terminals of the electric motor, a first driving circuit for rotating the electric motor in forward direction, the first driving circuit becoming operative

upon receipt of the first signal, a second driving circuit for rotating the electric motor in reverse direction, the second driving circuit becoming operative upon receipt of the second signal, and a relay circuit for closing the

5 first driving circuit into operative condition upon receipt of the first signal, closing the second signal and closing the short-circuiting circuit upon balance of the bridge circuit. Thus, the electric motor varies the resistance value of the resistance element by the rotation 10 thereof upon unbalance of the bridge circuit and the motor is stopped by the short-circuiting circuit upon balance of the bridge circuit.

The relay circuit may include a relay for selectively closing the short-circuiting circuit and the two driving 15 circuits. The relay closes the short-circuiting circuit upon balance of the bridge circuit, the first driving circuit upon receipt of the first signal and the second driving circuit upon receipt of the second signal, respectively.

20 The detecting circuit may be a complementary circuit composed of *pnp* and *npn* transistors, one of which selectively becomes conductive upon unbalance of the bridge circuit. Thus, the *pnp* transistor produces the first signal in the conductive condition thereof and the *npn* transistor produces the second signal in the conductive condition thereof.

25 There has thus been outlined rather broadly the more important features of the invention in order that the detailed description thereof that follows may be better understood, and in order that the present contribution to the art may be better appreciated. There are, of course, additional features of the invention that will be described hereinafter and which will form the subject of the claims appended hereto. Those skilled in the art 30 will appreciate that the conception upon which this disclosure is based may readily be utilized as a basis for the designing of other structures for carrying out the several purposes of the invention. It is important, therefore, that the claims be regarded as including such 35 equivalent construction as do not depart from the spirit and scope of the invention.

BRIEF DESCRIPTION OF THE DRAWINGS

40 A specific embodiment of the invention has been 45 chosen for purposes of illustration and description, and is shown in the accompanying drawings, forming a part of the specification, wherein:

FIG. 1 is a circuit diagram showing a first embodiment of the present invention; and

50 FIG. 2 is a circuit diagram showing a second embodiment of the present invention.

DESCRIPTION OF THE PREFERRED EMBODIMENTS

55 Referring to FIG. 1, there is shown a circuit according to a first embodiment of the present invention. It includes a photoelectric element *Bph* such as *CdS* cell, and a function resistor *Rv* operatively associated with a DC drive motor *M* in such a manner that the resistance value of the function resistor *Rv* is decreased when a current flows through the motor *M* in the direction of arrow *i*. The function resistor *Rv* is also operatively associated with exposure factors such as *F*-number and shutter time in such a manner that the combination of the exposure factors is varied in the direction toward under-exposure when the motor is driven in the direction for decreasing the resistance

value of the function resistor R_v , and that the combination of the exposure factors provides a proper exposure when the value of the resistance R_v is equal to the value of the photoelectric element R_{ph} .

Resistors R_3 and R_4 , equal in resistance value, cooperate with the photoelectric element R_{ph} and function resistor R_v to constitute a bridge circuit. An *npn* transistor T_1 and a *pnp* transistor T_2 have their respective bases connected with a balance output terminal a of the bridge circuit constituted by the photoelectric element R_{ph} and function resistor R_v , and have their respective emitters connected with the other balance output terminal of the bridge circuit constituted by resistors R_3 and R_4 . Thus, the transistors T_1 and T_2 constitute a complementary circuit which is a circuit for detecting the balance of the bridge circuit. The collector of the transistor T_1 is connected with the base of a *pnp* transistor T_3 through the resistor R_1 , and the collector of the transistor T_2 is connected with the base of an *npn* transistor T_4 through the resistor R_2 . The collector of the transistor T_3 is, in turn, connected with the collector of the transistor T_4 through serially connected resistors R_5 and R_6 . The emitters of the transistors T_3 and T_4 are connected with the positive and negative terminals of an electric power source E_b , respectively. An *npn* transistor T_5 and a *pnp* transistor T_6 , connected together in complementary relationship, have their respective bases connected with the midpoint between the resistors R_5 and R_6 , and have their respective emitters connected with one of the terminals of DC drive motor M (hereinafter referred to as "motor M' "). The collectors of the transistors T_5 and T_6 are connected with the positive and negative terminals of the electric power source E_b , respectively. Thus, the transistors T_3 , T_4 , T_5 and T_6 together constitute a drive circuit for the motor M . The other terminal of the motor M is connected with a common relay contact S_a which is operated by a relay coil L . A break contact S_b , adapted to be closed when there is no current flowing to the relay coil L , is connected with the emitters of the transistors T_5 and T_6 , and a make contact S_c , adapted to be closed when there is a current flowing to the relay coil L , is connected with the midpoint of the electric power source E_b . The opposite terminals of the motor M are short-circuited when there is no current flowing to the relay coil L . A *pnp* transistor T_9 has its emitter connected with the positive terminal of the electric power source E_b , its base connected with the collector of the transistor T_1 through a resistor R_7 , and its collector connected through a resistor R_{11} with an *npn* transistor T_8 for energizing the relay coil L . An *npn* transistor T_{10} has its emitter connected with the terminal of the electric power source E_b , its base connected with the collector of the transistor T_2 through a resistor R_8 , and its collector connected with the base of a *pnp* transistor T_7 through a resistor R_{10} . The emitter of the transistor T_7 is connected with the positive terminal of the electric power source E_b and the collector thereof is connected with the base of the transistor T_8 through a resistor R_9 . The emitter of the transistor T_8 is connected with the negative terminal of the electric power source E_b and the collector thereof is connected with one end of the relay coil L , whose other end is, in turn, connected with the positive terminal of the electric power source E_b . The transistors T_7 , T_8 , T_9 , T_{10} and the relay coil L together constitute a relay energizing circuit for selectively closing the com-

mon relay contact S_a with respect to the break contact S_b or to the make contact S_c .

Operation of the described circuit of the present invention will now be explained.

- 5 When the photoelectric element R_{ph} receives light, it presents a resistance as determined by its own characteristic. If the resistance value is smaller than that of the function resistor R_v , i.e., if the exposure determined by the combination of exposure factors such as 10 F-number, shutter speed, film sensitivity, etc. is in a condition of over-exposure, then the potential at the balance output terminal point a will be higher than the potential at the balance output terminal point b . If the difference between the two potentials is greater than 15 the threshold voltage between the base and emitter of the transistor T_1 , this transistor T_1 will become conductive and accordingly, the transistor T_3 will also become conductive. Since the transistor T_2 is in non-conductive state, the transistor T_4 will also be non-conductive. Thus, the transistor T_5 is ready to be driven. At the same time, the transistor T_9 will become conductive to detect the readiness of the motor M to be driven and accordingly, the transistor T_8 will conduct to energize the relay coil L . Energization of the relay coil L will cause the common relay contact S_a to be closed with respect to make contact S_c . A current will flow through the motor M in the direction of arrow i_1 to rotate the motor M , whereupon the function resistor R_v is driven in a direction to decrease its resistance 20 value while the exposure factors are driven in a direction toward under-exposure. When the potential difference between the points a and b becomes smaller than the threshold voltage between the emitter and base of the transistor T_1 , the transistors T_1 and T_2 will become 25 non-conductive. As a result, all transistors will become non-conductive to nullify the driving current to the motor M and also nullify the current to the relay coil L , so that the common relay contact S_a will be closed with respect to the break contact S_b , thus short-circuiting the opposite terminals of the motor M to apply an electromagnetic brake to stop the motor 30 quickly.

- If the resistance value of the photoelectric element R_{ph} is higher than that of the function resistor R_v , i.e., 45 if the exposure determined by the combination of exposure factors such as F-number, shutter speed, film sensitivity, etc. is in a condition of under-exposure, the potential at the point a will become lower than the potential at the point b . When the potential difference between the two points is greater than the threshold voltage between the base and emitter of the transistor T_2 , this transistor T_2 will become conductive and accordingly, the transistor T_4 will also become conductive. Since the transistor T_1 is in non-conductive state, the transistor T_3 will also be nonconductive. Thus, the transistor T_6 is ready to be driven. At the same time, the transistor T_{10} will become conductive to detect the readiness of the motor M to be driven and accordingly, the transistors T_7 and T_8 will conduct to energize the relay coil L . Energization of the relay coil L will cause the common relay contact S_a to be closed with respect to the make contact S_c , thus permitting a current to flow through the motor M in the direction of arrow i_2 . As the motor M is rotated, the function resistor R_v is driven in the direction to increase its resistance value 50 while the exposure factors are driven in a direction toward over-exposure. When the potential difference 55 between the points a and b becomes smaller than the threshold voltage between the emitter and base of the transistor T_2 , the transistors T_1 and T_2 will become non-conductive. As a result, all transistors will become non-conductive to nullify the driving current to the motor M and also nullify the current to the relay coil L , so that the common relay contact S_a will be closed with respect to the break contact S_b , thus short-circuiting the opposite terminals of the motor M to apply an electromagnetic brake to stop the motor 60 quickly.

between the points *a* and *b* becomes smaller than the threshold voltage between the emitter and base of the transistor T2, the transistors T1 and T2 will become nonconductive and thus, all transistors will become nonconductive. Thereupon, the opposite terminals of the motor M will be short-circuited to apply an electromagnetic brake to stop the motor quickly. In this way, the drive motor M acts as a damper when it is stopped, and this provides a very good damping of the servo system.

FIG. 2 shows another embodiment of the present invention in which the driving circuit for motor M' is provided by a single electric power source.

In the circuit of this embodiment, if the potential at the balance output terminal point *a'* is higher than the potential at the point *b'* and the potential difference becomes greater than the threshold voltage between the base and emitter of transistor T1', then npn transistor T1', for detecting the balance of the bridge, will become conductive. This renders conductive *pnp* transistor T3', *npn* transistor T6', *npn* transistor T8' and *pnp* transistor T9' which constitute a motor driving circuit, as well as *npn* transistor T12' and *pnp* transistor T11' which constitute a relay energizing circuit. On the other hand, *pnp* transistor T2', for detecting the balance of the bridge, is in non-conductive state, thus rendering non-conductive *npn* transistor T4', *pnp* transistor T5', *pnp* transistor T7' and *npn* transistor T10' which constitute the motor driving circuit. As a result, relay coil L' is energized to cause a common relay contact Sa' to be closed with respect to a make contact Sc', permitting a current to flow through motor M' in the direction of arrow *i*1'. As the motor M' is rotated, the function resistor Rv' is driven in a direction to decrease its resistance value and the exposure factors are driven in a direction toward under-exposure. If the potential at the point *a'* becomes lower than that at the point *b'* and the potential difference is greater than the threshold voltage between the base and emitter of the transistor T2', this transistor T2' will become conductive. Thus, transistors T4', T5', T7', T10' and T11' will all become conductive. Since the transistor T1' is in non-conductive state, transistors T3', T6', T8', T9' and T12' are also in non-conductive state. Therefore, the relay coil L' will be energized and the common relay contact Sa' will be closed with respect to the make contact Sc' to permit a current to flow through the motor M' in the direction of arrow *i*2', thus rotating the motor M'. At the same time, the function resistor Rv' will be driven in a direction to increase its resistance value while the exposure factors will be driven in a direction toward over-exposure. When the potentials at the points *a'* and *b'* become equal, all transistors will be rendered non-conductive to deenergize the relay coil L', so that the common relay contact Sa' will be closed with respect to the break contact Sb', thus short-circuiting the opposite terminals of the motor M' to apply an electromagnetic brake to stop the motor quickly.

With the circuit so-constructed and operable as described above, the aggravated damping effect (i.e., instability of the servo system) resulting from the moment of inertia of the movable members forming the servo system may be prevented by applying an electromagnetic brake through the short-circuiting of the motor armature winding to improve the damping effect and achieve the stabilization of the servo system. More-

over, any special damper means, speed feedback and the like are not required and this leads to the advantages that the constant speed need not be reduced (that is, any reduction in response speed may be obviated) and that the entire device may be made compact.

In the first and second embodiments of the present invention, the relay energizing circuit has been described as being controlled by using the collector current of the balance detecting transistors T1, T2 and the collector current of the transistors T3', T4' in the motor driving circuit, respectively, to detect the readiness of the motor driving circuit to drive the motor; whereas these are not the only means of control, but it will be apparent that other circuit arrangements may be available if only the readiness of the motor to be driven is detected to control the relay circuit.

Further, in the above-described embodiments, automatic exposure control is accomplished by driving the function resistor from the motor thereby to balance the bridge circuit, but will also be apparent that the effect of the present invention may equally be achieved by providing a diaphragm, filter or like means in front of the photoelectric element and causing the motor to displace such means thereby to vary the resistance value of the photoelectric element so as to balance the bridge circuit.

I believe that the construction and operation of my novel exposure determining device will now be understood, and that its advantages will be fully appreciated by those persons skilled in the art.

I claim:

1. An exposure determining device comprising:
an exposure detecting circuit including a photoelectric element adopted to receive light from an object to be photographed, the exposure detecting element producing a first signal in a case of under-exposure, a second signal in a case of over-exposure and a third signal in a case of proper exposure,
relay switch means having a first state and a second state, means for switching said relay switch means to said first state in accordance with said first signal and for switching said relay switch means to said second state in accordance with said third signal, means for setting at least one exposure factor, an electric motor rotatable in forward and reverse directions and connected to said exposure factor setting means to attain proper exposure,
a first motor driving circuit including said relay switch means and a first transistorized switch connected in series with said relay switch means, said first motor driving circuit being operative when said relay switch means is in said first state and when said first transistorized switch is "on" in accordance with said first signal,
a second motor driving circuit for the reverse rotation of said motor including said relay switch means and a second transistorized switch connected in series with said relay switch means, said second motor driving circuit being operative when said relay switch is in said first state and when said second transistorized switch is "on" in accordance with said second signal, and
a circuit for short-circuiting both terminals of said motor when said relay switch means is in said second state.

2. An exposure determining device according to claim 1, wherein said exposure detecting circuit includes

a bridge circuit having a variable resistor associated with said exposure factor setting means and a photoelectric element receiving light from the object to be photographed, and

a complementary circuit including PNP and NPN transistors for detecting the state of the bridge circuit.

3. An exposure determining device according to claim 1, wherein said relay switch switching means includes a transistor connected in series with a coil of said relay switch means, said transistor being conductive upon receipt of said first or second signal.

4. An exposure determining device according to claim 1, wherein said first motor driving circuit includes a first power source connected in series with said relay switch means and with said first switch means, and

said second motor driving circuit includes a second power source connected in series with said relay switch means and with said second switch means.

5. An exposure determining device according to claim 1, wherein said relay switch means is connected to said motor,

said first motor driving circuit includes a transistor which functions as a third switch means and is "on" upon receipt of said first signal,

said second motor driving circuit includes a transistor which functions as a fourth switch means and is "on" upon receipt of said second signal,

said first and second motor driving circuits have the common power source (E'_b),

said first switch means (T'_7) is connected between the positive terminal of the power source and a terminal of the motor,

said third switch means (T'_{10}) is connected between the negative terminal of the power source and the relay switch means,

said second switch (T_8) is connected between the negative terminal of the power source and the relay switch means, and

said fourth switch means (T'_9) is connected between the positive terminal of the power source and the relay switch means.
